Jack C. Roberts, Los Angeles County, Calif., assignor to
Saxton Electronics Corporation, Congers, N.Y., a corporation of New York

Filed Feb. 13, 1968, Ser. No. 10,557

Term of patent 14 years

(Cl. D26—14)

FIGURE 1 is a front, top perspective view of the wireless intercom showing my new design;

FIGURE 2 is a side elevational view thereof;

FIGURE 3 is an end elevational view thereof;

FIGURE 4 is a top plan view thereof; and

FIGURE 5 is a rear side view thereof.

The dominant features of my design are shown in full lines. The antennae is shown fragmentarily in FIGURES 2, 3 and 5 for convenience of illustration only.

I claim:

The ornamental design for a wireless intercom, substantially as shown and described.
